[57] CLAIM

The ornamental design for a container, as shown and described.

DESCRIPTION

FIG. 1 is a perspective view of the ornamental design of a container;

FIG. 2 is a top view thereof;

FIG. 3 is a bottom view thereof;

FIG. 4 is a left side view thereof;

FIG. 5 is a right side view thereof;

FIG. 6 is a front view thereof; and

FIG. 7 is a rear view thereof.

The container is usable as a receptacle for gratuities in the form of currency or coins and is generally meant to have the shape of a hop, as used in brewing of beer.

The broken line showing of a handle in FIGS. 1-3, 6 and 7 is for illustrative purposes only and forms no part of the claimed design.
